(57) **CLAIM**

The ornamental design for a guitar pick with fin as shown and described.

DESCRIPTION

FIG. 1 is a top front perspective view of a first embodiment of a guitar pick with fin, showing my design;

FIG. 2 is a front elevation view of the first embodiment of the guitar pick with fin;

FIG. 3 is a rear elevation view of the first embodiment of the guitar pick with fin;

FIG. 4 is a left elevation view of the first embodiment of the guitar pick with fin, with a right elevation view being a mirror image of the left elevation view;

FIG. 5 is a top plan view of the first embodiment of the guitar pick with fin;

FIG. 6 is a bottom plan view of the first embodiment of the guitar pick with fin;

FIG. 7 is a top front perspective view of a second embodiment of a guitar pick with fin, showing my design;

FIG. 8 is a front elevation view of the second embodiment of the guitar pick with fin;

FIG. 9 is a rear elevation view of the second embodiment of the guitar pick with fin;

FIG. 10 is a left elevation view of the second embodiment of the guitar pick with fin, with a right elevation view being a mirror image of the left elevation view;

FIG. 11 is a top plan view of the second embodiment of the guitar pick with fin; and,

FIG. 12 is a bottom plan view of the second embodiment of the guitar pick with fin.

The broken lines shown in the drawings depict portions of the guitar pick with fin that form no part of the claimed design.
